UNITED STATES PATENT OFFICE.

FRITZ R. JOHNSON, OF PROVIDENCE, RHODE ISLAND.

VANITY CASE.

Application filed June 11, 1925. Serial No. 36,368.

To all whom it may concern:

Be it known that I, FRITZ R. JOHNSON, a citizen of the United States, residing at Providence, in the county of Providence and State of Rhode Island, have invented certain new and useful Improvements in Vanity Cases, of which the following is a specification.

My invention relates to vanity cases or boxes adapted for the accommodation of powder.

The essential objects of my invention are automatic delivery of a certain quantity of powder, and in the convenient and available location of the latter.

Further objects are ready accessibility to the powder supply, and simplicity and inexpensiveness of construction.

To the above ends essentially my invention consists in such parts and in such combinations of parts as fall within the scope of the appended claims.

In the accompanying drawings which form a part of this specification—

Figure 1 is a side elevation of a closed vanity case embodying my invention,

Figure 2, a transverse section of the same, open,

Figure 3, a detail view of a powder pad or puff,

Figures 4 and 5, top plan views of the closure member showing the parts in closed and in partially open positions respectively, and

Figure 6, a bottom plan view of the same.

Like reference characters indicate like parts throughout the views.

In the form of my invention herein shown the case comprises a box or body 8, and cover 9 connected with the body by an external hinge 10. The body comprises a bottom or base 12, and a side wall 13 provided with an intermediate annular shoulder 14, above which is a projection 15 opposite the hinge. Integral with the top of the wall 13 is a downwardly inclined internal annular flange 16 provided with a horizontal annular lip portion 17. The flange and lip form a partition with a central opening 18. Below this partition is the compartment 19 forming the container for the powder. The closure 21 for the opening consists of a plate 22 having a lateral bead 23 adapted to rest on the lip 17, and a flange 24 depending from the bead adapted to frictionally enter the opening 18, and be maintained compara-

tively rigid with the partition. In the center of this plate is a rivet or pivot member 25 upon which is pivoted a movable plate 26 rotatably engaging the lower face of the closure plate provided with an elevated peripheral operating finger 27 passing through a marginal arcuate slot 28 in the plate 22. The closure plate has one or more, in this instance three, oblong arcuate holes 30 annularly arranged in an intermediate portion thereof. Similarly arranged openings 32 in the movable plate register with the holes 30. The openings are formed in this instance by cutting and bending from the material of the plate 26 downwardly inclined tongues or scoop members 33, integral with the plate, and constituting the boundary of one edge of the several openings 32, as at 34, which boundary is radially disposed, and transverse to the holes 30. Each scoop member or tongue 33 comprises in this instance a central or body portion 35 with upturned lateral lips 36.

When the plate 26, by the manual operation of the finger 27, is turned in the direction of the arrows shown in Figures 4 and 5, the members 33 scoop powder from the supply in compartment 19. The powder is forced upwardly along the inclined faces of the scoops to points above the plane of the plate 22 where the advance of the plate 26 masses the elevated powder into a small pile upon the plate 22 adjacent one end of each hole. One such pile of powder is diagrammatically indicated by 38 in Figure 4. In Figure 5 the plate 26 is shown in intermediate position of progress, and Figure 4 shows the position of said plate after the completion of the pile formation, with the holes 30, 95 completely closed. The piles of powder are in convenient and available position for the user to touch with a powder puff or pad 40.

The depression in the partition is intended for the accommodation of the powder puff 100 when not in use.

The cover 9 comprises a top 44 and side 45 provided with a marginal recess 47 adapted to receive the projection 15 when the cover is closed. A mirror 49 is held against the top 44 by a retaining ring 50.

The closure is removable from the opening 18 by the insertion of a finger nail or sharp tool beneath the bead or shoulder 23 and lifting or prying the same. When the closure plate is removed the compartment 19 is accessible for a fresh supply of powder.

I claim:—

1. In a vanity case, a box comprising a bottom, a side, a closure plate supported by the side above the bottom and provided with a hole, a plate loosely engaging the lower face of the closure plate movable there beneath and provided with an opening, and a downwardly directed scoop member upon the movable plate beside the opening in alignment with the hole.

2. In a vanity case, a box, a partition in the box provided with an opening, a closure member in the opening provided with a hole, a plate pivotally engaging the closure member, and an inclined scoop member on the plate registrable with the hole when the plate is turned.

3. In a vanity case, a box, a partition carried by the box provided with an opening, a closure member comprising a plate, a peripheral shoulder on the plate overlapping the partition around the opening, and a flange depending from the shoulder frictionally engaging the partition in the opening, said plate being provided with a hole, and a plate pivotally mounted on the lower face of the closure plate concentrically thereof, and a radially disposed depending inclined scoop member carried by the second plate registrable with the hole when the last mentioned plate is turned.

4. In a vanity case, a box, a cover engageable with the top of the box, a partition in the upper portion of the box below the cover and provided with an opening, a plate upon the partition closing the opening and

provided with a curved slot and with a hole, a pivot member in the plate concentric with the slot, a second plate mounted upon the pivot member in contact with the first plate and provided with an opening equidistant with the hole from the pivot member, a depending scoop member integral with the second plate adjacent the last mentioned opening, and an elevated finger on the second plate extending loosely through the slot.

5. In a vanity case, a box, a cover hingedly connected to the box, a partition supported in the top of the box provided with a depressed central portion and with an opening in the central portion, a closure member in the opening provided with a hole, a plate pivotally engaging the lower face of the closure member, an inclined scoop member on the plate registrable with the hole when the plate is turned.

6. In a vanity case, a box, a cover hingedly connected to the box, a horizontal partition carried by the box provided with an opening, a closure member in the opening provided with annularly disposed holes, a plate pivotally mounted upon the closure member concentrically of the holes provided with annularly arranged openings registrable with the holes, and radially disposed downwardly directed scoop members adjacent the last mentioned openings comprising inclined body portions integral with the plate and lateral upturned lips upon the body portions.

In testimony whereof I have affixed my signature.

FRITZ R. JOHNSON.
